UNITED STATES PATENT OFFICE.

PAUL SOTAK, OF HOMER CITY, PENNSYLVANIA.

RAIL-JOINT AND SUPPORTING-TIE.

1,144,567.

Specification of Letters Patent. Patented June 29, 1915.

Application filed April 19, 1915. Serial No. 22,864.

To all whom it may concern:

Be it known that I, PAUL SOTAK, a subject of the King of Hungary, residing at Homer City, in the county of Indiana and State of Pennsylvania, have invented certain new and useful Improvements in Rail-Joints and Supporting-Ties, of which the following is a specification.

This invention relates to certain new and useful improvements in rail joints and supporting ties.

An object of the present invention is to provide a tie and rail construction in which the ties and rails are held in interlocked position without the use of auxiliary fastening means.

A further object of the invention is to provide interlocking rails and ties in which the meeting ends of the rails form a scarf joint, the rails being associated with the ties at their meeting ends in a manner to prevent separating movement of the rails.

With the above and other objects in view that will appear as the nature of the invention is better understood, the same consists in the novel combination and arrangement of parts hereinafter fully described, illustrated in the accompanying drawings, and pointed out in the appended claim.

In the drawings forming a part of this application and in which like designating characters refer to corresponding parts throughout the several views:—Figure 1 is a side elevational view of a supporting tie built in accordance with the present invention, with the rails supported thereon, the rails being shown in section. Fig. 2 is a top plan view of a portion of a track. Figs. 3 and 4 are detail perspective views of the opposed meeting rail ends. Fig. 5 is a side elevational view of the meeting rail ends in assembled position with the supporting tie shown in section, and, Fig. 6 is a detailed perspective view partly in section of a portion of one of the supporting ties which illustrates the construction of tie forming the rail seat.

Briefly described, the present invention aims to provide a rail joint in which the meeting ends of rails are adapted to be held relatively immovable and associated with supporting ties in such manner as to interlock therewith, whereby the use of fastening bolts and nuts, etc., is obviated. The meeting rail ends are of the scarf type so that a bridge piece overlies the contacting faces of the

rail ends while the base flanges or lower ends of the rails carry means that are adapted to coöperate with the supporting tie to prevent movement of the rails in a longitudinal direction, while upward movement of the rails is prevented by overhanging ledges or shoulders forming a part of the supporting ties.

Describing the invention in detail, the reference numeral 10 designates the supporting ties which are provided adjacent each end with a cut-away portion to provide a seat for the rails supported thereon.

A detail view of one of the rail seats is shown in Fig. 6 wherein the bottom wall of the seat is upwardly inclined from each side edge toward the center as at 11 to provide a substantially anticlinal base, this construction being clearly shown in Fig. 1. The end walls of the seat portion extend inwardly as at 12 to provide overhanging shoulders adapted to engage the base of the rails. An opening 13 is formed in each of the inclined portions 11 at the lower edges thereof and spaced between the side edges of the tie 10, the purpose of which will presently appear.

The rails 14 are substantially triangular in cross-section as shown in Fig. 1 and include solid web and base portions 15, the bottom faces of the rails being cut-away to provide a substantially inverted V-shaped bottom face 15', while the treads are designated 16. As shown in Fig. 4, the tread 16 is cut-away at its end to provide a semi-cylindrical recess 17 adapted for the reception of the semi-cylindrical projection 18 carried by the tread portion 16 of the opposed rail end, as shown in Fig. 3. In assembled position, as shown in side elevation in Fig. 5, the projection 18 is seated within the recess 17 while the end walls of the rail ends 14 lie juxtaposed. Each lower corner of the contacting faces of the rail ends is provided with a depending lug 19 adapted for reception in the recesses 13 formed in the tie 10 so that relative longitudinal movement of the rails 14 is prevented.

As shown in Fig. 1, there is a slight space between the lower sides 15 of the rails and the overhanging shoulders 12, this space permitting the rails 14 to slide toward each other upon the inclined portions 11 of the tie until the lugs 19 are positioned over the recesses 13, at which time the said rails 14 are lowered by their own weight and assume the position shown in Figs. 1 and 5. It will

be noted by this construction that relative longitudinal movement of the ties in a separating direction is prevented by the lugs 19 being received in the recesses 13, while 5 upward movement of the rails is prevented by the overhanging shoulders 12 engaging the sides 15 of the said rails.

What I claim as new is:—

10 A device of the class described, including meeting rail ends, supporting ties therefor including seat portions, each seat portion formed of upwardly converging sides adapted to provide a substantially anticlinal base,

overhanging shoulders formed above said seat, said shoulders adapted to engage the 15 lower side edges of said rail to prevent upward movement thereof, and coöperating means between the rail ends and seat to prevent relative longitudinal movement of the rails.

20

In testimony whereof I affix my signature in presence of two witnesses.

PAUL SOTAK.
